UNITED STATES PATENT OFFICE.

HENRY T. PAISTE, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

FUSE TERMINAL.

Application filed March 31, 1922. Serial No. 548,492.

To all whom it may concern:

Be it known that I, HENRY T. PAISTE, a citizen of the United States, residing in Philadelphia, Pennsylvania, have invented **Fuse Terminals**, of which the following is a specification.

One object of my invention is to provide a novel form of fusible element and terminal therefor particularly designed for use in fuse plugs, and which, in addition to being of such construction as to permit of its economical and inexpensive manufacture, shall be of such a nature that it may be easily and conveniently assembled in or applied to a fuse plug, fuse capsule or other suitable supporting or receiving structure.

Another object of the invention is to provide a novel form of terminal for quickly and conveniently connecting one end of a fusible link to a fuse plug capsule, fuse plug, or cutout device, which shall be simple, substantial and of such a nature as to permit of the quick and convenient renewal of the fusible element or link when this has been fused by an excessive current flow or otherwise broken.

These objects and other advantageous ends I attain as hereinafter set forth, reference being had to the accompanying drawings, in which,

Figs. 1 and 2 are respectively an edge elevation and a section on the line 2—2, Fig. 1, illustrating a fusible link and terminal therefor constructed in accordance with my invention;

Fig. 3 is a plan of the device shown in Figs. 1 and 2;

Figs. 4 and 5 are vertical longitudinal sections illustrating my invention as applied to a well known form of fuse plug; and

Fig. 6 is a vertical section illustrating my invention as applied to a fuse capsule.

In Figs. 1 and 2 of the above drawings, 1 represents a thin elongated strip of relatively fusible sheet material such as zinc, copper or other metal or alloy, having one end laterally extended to constitute a head 3, adjacent which the body of the strip is notched or otherwise cut away as indicated at 2—2 so that it has a predetermined minimum cross sectional area such as will insure fusing at this point upon the occurrence of a predetermined current flow.

The terminal plate for the fusible element 55 is provided by an elongated body of sheet

metal, such as brass or copper, folded upon itself at substantially its middle point to provide a body portion 4 whose ends 5 are bent substantially at right angles in opposite directions and in the same plane so that they are together substantially circular in plan, as shown in Fig. 3. The width of this body 4 is equal to or slightly greater than the width of the head 3 of the fusible element which is designed to lie between the folds of said body after said element itself has been extended through a slot 6 at the middle of the apex of said portion 4.

The length of the head 3 is slightly greater than the height of the terminal body 4 and said head is formed with a kerf or cut about midway of its top edge to provide two tongues 7—7 which are preferably bent in opposite directions so as to lie parallel and in engagement with the top or outer surfaces of the wings 5 of the terminal member 4. Obviously both the fusible element 1—3 and the terminal element 4—5—5 may be stamped or struck up from suitable pieces of sheet metal and may be thereafter assembled in the forms shown in Figs. 1 to 3 inclusive. They are then available for sale for manufacturing or renewal purposes or they may be at once applied to fuse plug bodies such as indicated at 8 in Figs. 4 and 5.

These bodies are customarily made of vitreous insulating material such as porcelain and each has at its closed end an elongated opening through which may be placed the fusible element 1 and the body portion 4 of the terminal plate. Thereafter the free end of said fusible element is bent laterally and extended through a notch or recess 9 adjacent the open end of the body 8, on the outer portion of which it is soldered or otherwise electrically connected to the threaded shell 10 customarily mounted thereon. The wings 5—5 of the terminal plate lie centrally upon the outer face of the closed end of the fuse plug body so as to constitute one of the terminals of said plug, whose second terminal is constituted by the threaded shell 10.

When used in fuse capsules such as illustrated in my application #357,536, filed February 10, 1920, the terminal plate 4—5—5 is applied to a porcelain capsule body 12 as shown in Fig. 6, so that its body 4 extends through the closed end of said

capsule body; the fusible element, after passage through an edge notch 13, being bent back over the outside surface of said capsule and finally projected outwardly upon 5 the shoulder portion 14 thereof.

In this particular case the fusible element with its terminal plate may be quickly applied to and assembled with the capsule with a minimum of labor, and even when 10 used with a fuse plug of the ordinary construction, may likewise be assembled with the utmost convenience and at a minimum expense. In the event of the fusing of the element 1 by reason of excessive current flow 15 or for any other reason, it may be replaced with the utmost ease in a minimum of time and with but little expense.

I claim:

1. A terminal plate consisting of a body 20 of sheet metal folded into substantially U-shaped form and having a slot at its apex; and a fusible link having a head located within the fold of the body.

2. A terminal plate consisting of a folded 25 body of sheet metal having a laterally extending contact portion; with a fusible link extending through the folded body and including a head portion lying between the parts of said body.

3. A terminal plate consisting of a folded 30 body of sheet metal having a laterally extending contact portion; with a fusible link extending through the folded body and in-

cluding a head portion lying between the parts of said body, a portion of the head of 35 the link being turned over said contact portion of the body.

4. The combination of a fuse terminal 40 consisting of two contact portions and a substantially U-shaped body portion joining said contact portions; and a fusible link having one end located in the shaped body portion.

5. The combination of a terminal plate 45 consisting of two contact parts and a substantially U-shaped body joining said parts; with a fusible link passing through an opening adjacent the apex of said body and having a head lying between the side portions 50 of the body.

6. The combination of a terminal plate 55 consisting of two contact parts and a substantially U-shaped body joining said parts; with a fusible link passing through an opening adjacent the apex of said body and having a head lying between the side portions 60 of the body, said head having portions turned over the contact parts of said plate.

7. A fuse terminal plate consisting of a substantially U-shaped body of sheet metal 65 having the ends of its side members laterally extended in the same plane to form contact parts, there being an opening through the apex portion of the body for a fuse link.

HENRY T. PAISTE.
